UNITED STATES PATENT OFFICE.

HARTFORD SWEET, OF BROOKFIELD, ILLINOIS.

WICK-DOUBLER.

1,345,280.

Specification of Letters Patent. Patented June 29, 1920.

Application filed March 29, 1919. Serial No. 286,013.

To all whom it may concern:

Be it known that I, HARTFORD SWEET, a citizen of the United States, residing at Brookfield, in the county of Cook and State 5 of Illinois, have invented a new and useful Wick-Doubler, of which the following is a specification.

This invention has reference to wick doublers, and its object is to double a tubular wick upon itself for use in connection with the iodin applicator shown and described in my application No. 301,351, filed June 2, 1919.

The iodin applicator comprises a tube 15 with an intermediate contracted portion in which there is introduced a doubled tubular wick or swab containing a short glass sleeve of a size to fit in the main tube, with the wick housing it, to the contracted portion of 20 the applicator tube, which latter is sealed at the ends and contains a quantity of iodin or other suitable preparation.

The invention comprises an instrument 25 with a holder at one end, which holder may be inserted in a tubular wick passed through a short glass sleeve, whereby to hold the wick and sleeve on the end of the instrument. Then a slid able part of the instrument may be pushed along the latter with 30 the portion of the wick surrounded by the glass sleeve and the sleeve itself held against movement with the slid able member, which latter engages that part of the wick, then in single-ply, around the instrument, and 35 pushes or doubles such part of the wick about the glass sleeve and upon itself. The sleeve and the doubled or two-ply wick may then be removed from the instrument and the wick cut off to a suitable length, or while

40 still on the instrument may be cut off to the desired length and the instrument used to introduce the double wick into a container for the iodin or other material employed. The extent of introduction is determined by 45 a contracted portion of the container, which may be of glass and sealed at one end, before the double wick or swab is introduced. The instrument is then removed leaving the wick in place with the glass tube embedded in the 50 wick serving as a stop, and then the other end of the container is sealed, thus preserving the contents of the container from loss or contamination. Such container, however, is of a nature permitting it to be readily 55 ruptured at the constricted portion so that the contents become accessible. The appli-

cator is particularly valuable for the dressing of wounds and may form part of an emergency kit.

The invention has to do particularly with 60 the rapid formation of the doubled wick or swab and means for readily introducing it into the container.

The invention will be best understood from a consideration of the following detailed description taken in connection with the accompanying drawing forming part of this specification, with the understanding, however, that the invention is not confined to any strict conformity with the showing 65 of the drawing, but may be changed and modified so long as such changes and modifications mark no material departure from the salient features of the invention as expressed in the appended claims. 75

In the drawing:—

Figure 1 is an elevation of the doubling tool showing a wick and glass sleeve, in section, applied thereto.

Fig. 2 is a similar view at right angles to 80 the showing of Fig. 1 and showing the movable member for effecting the doubling of the wick partially advanced in such operation.

Fig. 3 is a longitudinal section on the line 85 3—3 of Fig. 1 but drawn on a larger scale.

Fig. 4 is a section similar to that of Fig. 3 but confined to the left hand portion thereof and showing holding prongs projected. 90

Fig. 5 is an elevation of the member provided with the prongs.

Fig. 6 is a view, partly in longitudinal section and partly in elevation, of a modified form of the tubular instrument. 95

Fig. 7 is a longitudinal section of the doubled wick or swab inclosing the glass sleeve.

Fig. 8 is a longitudinal section of still 100 another form of the invention.

In the drawing, there is shown a tube 1 of appropriate length constituting a body member, and inserted in one end of the tube 1 there is a tubular nose 2 having a continuation 3 with diametrically opposite longitudinal slots 4 therein, the extremity of the nose being closed as indicated at 5.

Within the tube 1 is another tube 6 concentric with the tube 1 and extending away from the nose 2 to a like extent, the two 110 tubes being secured together at their rear ends in concentric, spaced relation by a ring

- 7 to which both tubes may be soldered or otherwise fixed. It will be understood that other means may be employed for holding the two tubes in fixed relation to each other.
- 5 The tube 6 is cut away on diametrically opposite sides, as shown at 8, to form tapering fingers 9, each terminating in a prong 10 projecting laterally from the free end of the finger in position to project into a slot 4.
- 10 The normal tendency of the fingers is to approach until in contact, in which case the prongs 10 are within the confines of the continuation 3 of the nose 2.

Surrounding the body tube 1 at the rear 15 end thereof and fixed to said body member by a spacing ring 11 is another tube 12 constituting a handhold. The tube 12 is considerably shorter than the body tube 1 and mounted on said body tube is a longitudinally movable sleeve 13 having a range of travel from abutting relation with the handhold 12 to a position beyond the nose end 2.

In Fig. 3 the tubes 1, 6, 12 and 13 are shown as concentrically arranged tubes 25 considerably spaced from each other in their concentric relation, but it will be understood that these tubes may have only such spacing where they have relative movement on each other to permit such movement 30 without binding.

The rear end of the tube 13 is entered by a tubular push piece 14 having a head or thumb piece 15 at the end remote from that entering the tube 13. The push piece 14 is so arranged that it is capable of limited longitudinal movement in telescoping relation to the tube 13, and fast to the head or thumb piece 15 is a rod 16 extending lengthwise of the push piece and movable therewith and through a guiding collar 17 fast in the rear end of the tube 6 and then carried forwardly to about the rear end of the nose piece 2. Between the collar 17 and the thumb piece 15 there is confined a 40 spring 18 surrounding the rod 16, the tendency of the spring being to retract the rod 16 but is yieldable to a force applied to the thumb piece 15 to push the forward end of the rod 16 between the approached 45 ends of the fingers 9. Where the prong ends of the fingers 9 come in contact, such fingers are bent to provide bevel shoulders 19 in the path of the forward end of the rod 16 so that when the push piece 14 is forced 50 into the tube 13 against the tendency of the spring 18 the forward end of the rod 16 engages the bevel shoulders 19 and thereby spreads the forward ends of the fingers 9, and causes the projection of the prongs 10, this being shown in Fig. 4. When pressure 55 upon the head 15 is released the spring 18 returns the parts to their normal position shown in Fig. 3, thereby retracting the prongs 10 so that they no longer project

beyond the surface of the extension 3 of 65 the nose 2.

When the instrument is to be used a short sleeve 20, which may be and preferably is made of glass tubing, has a piece of hollow wicking 21 threaded through it, such wicking being of tubular weave and may be cotton wicking. The wicking projects beyond one end of the sleeve 20 to an extent permitting the projecting end to be pushed upon the forward end of the body tube 70 1 to a desirable extent and the sleeve 20 is applied to the extension 13 of the nose 2, whereupon, the push piece 14 is advanced causing the prongs 10 to project and engage that portion of the wicking forward 75 of the sleeve 20. Now, the movable sleeve or tube 13 is pushed forwardly, engaging that end of the hollow wick 21 upon the forward end of the body tube 1, thereby pushing the wick in front of it toward the 80 sleeve 20, thus forcing the wick over the sleeve. Because the sleeve 20 is held onto the nose extension 3 by the projected prongs 10, the wicking is compelled to double on itself so that there are two thicknesses of 85 wicking, one outside of the other and the glass sleeve 20 is housed in the doubled wicking between the two layers thereof at one end of such doubled wicking. If the original wicking be of considerable length 90 the doubled portion is cut off at a suitable distance from the sleeve 20 so that when placed in a container, as described in the aforesaid application, the end of the doubled wicking containing the glass sleeve 100 is lodged on one side of the contracted portion of the container and the free ends of the doubled wicking project through the contracted portion to the other side of the latter.

105 The instrument may be utilized for placing the doubled wicking into the container and this may be done without removing the doubled wicking after the doubling has been accomplished, since the free ends of 110 the doubled wicking may be cut off to the desired length while the prongs 10 are still in the projected position. When the doubled wicking or swab is placed in the container to the desired position the instrument may be released from the wicking by retracing the prongs 10 and the device may be easily withdrawn from the container, leaving the wicking therein. In Fig. 7 the completed swab is shown inclosing the 115 sleeve 20 and the wicking 21 indicated in the doubled condition.

In Fig. 6 a simplified form of the instrument is indicated, showing a rod 22, which may be of tubular form if desired, and at 120 one end this rod has an enlarged or handle portion 23 while at the other end there is a nose projection 3^a provided with exterior

screw threads 24. Mounted on the rod 22 so as to have relative longitudinal movement with respect thereto is a sleeve 25. The rod 22 carries an exterior collar 26 fixed thereto and the sleeve 25 has at one end an interior collar 27 fixed thereto. The sleeve or tube 25 has a range of movement between the handle 23, which is larger than the rod 22, and the collar 26, this range of movement being sufficient to carry the forward end of the tube 25 over and beyond the nose end 23. When it is desired to double the wick around the glass sleeve 20, the wick is threaded through the sleeve as in the structure of Fig. 1, and the projecting portion of the sleeve is threaded over the forward end of the rod 22. Then the rod 22 is turned about its longitudinal axis so that the screw-threads 24 move into the sleeve 20 in engaging relation to the portion of the wick there located and the parts are so proportioned that the wick is forced into sufficiently firm engagement with the inner face of the glass sleeve 20 to hold the glass sleeve in place. Now, on pushing forward the tube 25 the adjacent end of the wicking is engaged thereby and returned over the sleeve 20 and beyond the latter, thus doubling the wick in the same manner as in Fig. 1 and associated figures. Then by cutting off the surplus wick the doubled wick may be introduced into the container to the desired point and the doubling instrument may be withdrawn by unscrewing the end 3^a of the rod 22 from engagement with the wicking inside of the sleeve 20.

In Fig. 8, which illustrates still another form of the invention, there is shown a tubular body member 28 contracted at the forward end into a tubular neck 29 open at both ends, while the rear end of the body member is closed by a cap 30. Within the body member are fingers 31 joined at the rear ends by a yoke 32 between which and the cap 30 the body member houses a spring 33, connected to the cap and to the yoke, thereby constantly tending to retract the fingers 31.

The forward ends of the fingers project through the neck 29 and are there provided with spear heads 34 so that these heads will tend to confine a sleeve 20 between them and the end of the body 28, which latter, where joining the neck 29, forms a shoulder or abutment 35.

Surrounding the body 28 is a longitudinally slidable tube 36 having longitudinal slots 37 to pass headed pins 38 on the respective fingers 31. A spring 39 carried by one of the fingers 31 and bearing against the other finger imparts to the fingers a spreading tendency.

When the fingers 31 are moved toward each other by the application of force applied to the headed pins 38, the spear heads

34 will overlap similarly to the action of the blades of shears and then a sleeve 20 with a piece of tubular wicking 21 threaded therethrough may be slipped upon the neck 29 with the extended portion of the wick 70 over the adjacent portion of the body 28. On releasing pressure upon the pins 38 the spear heads 34 will separate and confine the sleeve 20 between them and the shoulder 35. By providing some play where the pins 38 75 extend through the body member 28 the heads 34 will engage and hold the sleeve 20 with sufficient force against the shoulder 35.

Now, on moving the tube 36 lengthwise of 80 the body member 28, the wicking 21 is engaged as in the other structures and returned upon itself so as to house the sleeve 20. Then by pressure applied to the pins 38 the heads 34 are moved out of the way of 85 the sleeve and the doubled wick housing the sleeve 20 is readily removed from the instrument, or the wicking may be cut off to the desired length and introduced into the container of the applicator in the manner hereinbefore described. The spear heads 34 may be so shaped as to avoid catching in the wicking when the latter is being applied to the instrument. 90

What is claimed is:—

1. An instrument for the purpose described, comprising an elongated body portion with a nose at one end of a size to receive a short sleeve with a piece of wicking traversing it, and with the body portion adjacent to the nose end shaped to receive the wicking where extended beyond the sleeve, and a slidable tube on the body portion movable against and over the wicking and over the sleeve on the nose portion, to double the wicking upon itself in housing relation to the sleeve on the nose portion. 100

2. An instrument for the purpose described, comprising an elongated body portion with a nose at one end of a size to receive a short sleeve with a piece of wicking traversing it, and with the body portion adjacent to the nose end shaped to receive the wicking where extended beyond the sleeve, and a slidable tube on the body portion movable against and over the wicking and over the sleeve on the nose portion, to double the wicking upon itself in housing relation to the sleeve on the nose portion, 105 said instrument having means at the nose portion for 110

engaging the wicking traversing the sleeve to hold the wicking and sleeve against escape from the nose portion while the wicking is being doubled over the sleeve and nose portion by the action of the slidable tube. 115

3. An instrument for the purpose described, comprising an elongated body portion with a nose at one end to receive a sleeve traversed by a hollow wick and with 130

- a part of the body portion next to the nose also entering the wick, retractile prongs normally within and movable oppositely through the nose to hold the wick-receiving sleeve on said nose extension, a manually operable member within the body portion and movable into engagement with the prongs to project them, and a tubular member movable lengthwise of the body portion to engage and fold that part of the wick on the body portion upon itself over and into housing relation to the sleeve on the nose projection.
4. An instrument for the purpose described, comprising an elongated tubular body portion, another tubular member withing the tubular body member and terminating at one end in spring fingers each having an outwardly directed prong at its outer end,
- 5 20 a nose member at the outer end of the body portion having a projection with openings through its side wall for the passage of the prongs, said prongs being projectable through the openings and having a normal tendency to retract, a manually operable longitudinally movable member within the casing having a range of travel to engage the prong portion of the second-named tubular member and project the prongs through
- 25 30 the nose extension, and another tubular member mounted on the tubular body member to move lengthwise thereof beyond the nose extension of the body member.
5. An instrument for the purpose described, comprising an elongated tubular member having a nose at one end with a projection having side openings, a tubular member slidable along the first-named tubular member to a point beyond the nose
- 35 40 extension, spring fingers within and fast to the body member and projecting into the nose extension and there provided with prongs shaped to be projected sidewise

through the openings in the nose extension, said fingers having a normal tendency to 45 retract, and a push rod having manipulating means at the end of the body member remote from the nose, said rod being of a length to extend between and project the prong ends of the fingers, and a spring for 50 normally retracting the push rod.

6. An instrument for the purpose described, comprising an elongated body portion with means at one end to receive and hold a short sleeve with a piece of tubular 55 wicking threaded through it, and means on the body portion for doubling the wicking upon itself in housing relation to the short sleeve.

7. An instrument for the purpose described, comprising an elongated body portion with holding means for a short sleeve with a piece of tubular wicking threaded through it, said holding means including laterally projectable and retractable devices 65 arranged to be moved into the path of application of the sleeve and wicking to and their removal from the body portion.

8. An instrument for the purpose described, comprising an elongated body portion having means at one end for the application to and removal therefrom of a short sleeve with a piece of tubular wicking threaded therethrough, means on the body portion movable lengthwise thereof to 75 double a portion of the wicking projecting through the sleeve upon itself in housing relation to the sleeve, and laterally projectable and retractable means carried by the body portion for holding the sleeve and 80 wicking on the body portion during the doubling operation.

In testimony that I claim the foregoing as my own, I have hereto affixed my signature.

HARTFORD SWEET.
